UNITED STATES PATENT OFFICE.

HENRY JEFFERSON DAVIS, OF WAYNESBORO, GEORGIA, ASSIGNOR OF ONE-FOURTH TO
R. C. NEELY AND ONE-FOURTH TO J. F. NEELY, BOTH OF WAYNESBORO, GEORGIA,
AND ONE-FOURTH TO ROBERT DAVIS, OF TENNILLE, GEORGIA.

VENDING-MACHINE.

1,280,417.

Specification of Letters Patent. Patented Oct. 1, 1918.

Application filed May 1, 1915. Serial No. 25,203.

To all whom it may concern:

Be it known that I, HENRY JEFFERSON DAVIS, a citizen of the United States, and resident of Waynesboro, county of Burke, 5 and State of Georgia, have invented certain new and useful Improvements in Vending-Machines, of which the following is a specification.

The present invention relates to improvements in vending machines and particularly to machines intended for vending liquid in bottles. The embodiment of the invention illustrated has been designed especially for vending bottles of coca cola, cherry cola, 10 ginger ale, sarsaparilla, etc., and has for its object to provide a mechanism adapted for this purpose which will be free from many of the objections that have been raised to the constructions heretofore proposed or employed 15 for this purpose. Experience has shown that bottles of the character employed for the purpose referred to cannot be successfully handled by vending machines which are adapted for dispensing cigars or packages of 20 other forms. It is, of course, necessary in order to have a successful machine that provision be made for supporting a relatively large number of bottles and it is found that there is a great tendency for the upper layers 25 of such a series to become so compact or interengaged as to form a "bridge" between opposite walls of the compartment in which they are arranged that will be sufficiently strong to support the bottles above it whereby when the lower layer or layers have been 30 delivered from the machine, the latter becomes inoperative and will not respond to the desired action on the insertion of a coin and manipulation of the parts in the usual 35 manner.

Further, with machines heretofore proposed for the same general purpose there has been no provision for saving the empty bottles and this causes a relatively high loss as 40 the value of the bottles represents a considerable part of the necessary capital invested in such an enterprise.

The present invention provides means by 45 which many of the objections, including those above noted, that have been raised against machines theretofore proposed for the same general purpose are avoided, and provides a mechanism by which, regardless of the number of bottles placed in the ma-

chine, there can be no failure to deliver one 55 upon properly actuating the parts until the last bottle has been dispensed. It is intended that a machine constructed in accordance with the present invention shall not require the constant care of an attendant and as it is 60 not desirable to provide a common drinking glass or cup, or to drink the contents of the bottles obtained from the machine directly therefrom, means are provided for automatically delivering with each bottle a drinking 65 straw.

In the accompanying drawings Figure 1 is a front elevation of a machine having its parts constructed in accordance with the present invention;

Fig. 2 is a side elevation;

Fig. 3 a side elevation with the casing broken away;

Fig. 4 is a vertical sectional view of the machine through the bottle and straw delivering devices;

Fig. 5 is a front elevation with part of the casing shown in section;

Fig. 6 is a sectional view substantially on the line 6—6 of Fig. 4;

Fig. 7 is a detail view of a portion of the coin discharging means;

Fig. 8 is an enlarged sectional view of the bottle cap removing means.

It will be understood that in the drawings many of the features are illustrated more or less diagrammatically; for example, the inclosing casing. Referring to the drawings 1 designates a suitable casing which is provided with a suitable compartment for the bottles to be sold, said compartment having an inclined floor that, as shown, does not extend continuously from the rear wall to the front wall of the casing, but includes two main sections connected by a substantially vertical wall 2 which is slightly higher than the diameter of the bottles to be vended and is positioned in the rear of the forward edge of the main floor section. The forward section of said floor 85 does not extend on the same angle throughout its length, but the front portion thereof is at a considerable angle to the portion in the rear thereof. The forward end of said floor extends through an opening in the 90 front wall of the main casing and in advance of said opening, on a shaft 4 is mounted the bottle and straw delivering device. 95 100 105

As shown, this device comprises two disks 5 connected by an intermediate sleeve that is loosely supported on the shaft 4, the latter being mounted in suitable bearings in the 5 walls of the casing and having secured thereon at one end, outside of said casing, an operating handle 4^a. Each of the disks 5 is provided with aligned peripheral pockets 5^a, such pockets being of a depth slightly less 10 than the diameter of the bottles to be accommodated therein. As shown in Fig. 5, said disks are preferably positioned or separated so that they will both engage the body of the bottle, the tapered neck thereof projecting 15 beyond the left hand disk of the delivery device. To the sleeve connecting the disks 5 or to a hub projecting from the right hand disk (Fig. 5) is secured a gear 6 having on one face a series of projections 6^a corresponding 20 in relative position to the pockets 5^a of the delivery device. A pawl 7 mounted on an arm 7^a projecting from a sleeve connected to the handle 4^a, or to the shaft 4 on which the handle is secured as above described, is 25 adapted to engage the lugs 6^a to impart intermittent rotary movement to the delivery device as the handle is rocked forward. A suitable spring acts to normally hold the handle 4^a in the upright position shown in 30 the drawings in which the pawl 7 is out of engagement with the gear 6. A torsion spring coiled about the shaft, as at the left hand end, and connected thereto and to the casing or any relatively stationary member 35 may be employed for this purpose. Said pawl is normally maintained in the position shown in Fig. 3, by the action of a counter-weight 7^b and spring 7^c and in this position it will be seen that the notch at the forward 40 end of said pawl is radially above the adjacent lug or projection 6^a on the gear 6. Therefore, if the lever is actuated with the 45 parts in this position there will be no engagement between the pawl 7 and the gear 6 and no movement will be communicated to the bottle delivering device. At its forward end the pawl 7 is provided with a coin receptacle 7^d that normally lies below the inner end of a receiving chute 8, the inlet 50 mouth of which is in the front wall of the casing 1. When a coin of the proper denomination and weight is deposited in the chute 8 it will be received in the pocket or receptacle 7^d and depress the pawl 7 against the action of the opposed counter-weight and spring sufficient to bring the notch thereof into radial alignment with the adjacent lug 6^a. Then as the handle 4^a is rocked forward 55 the gear 6 and bottle delivering device will be turned sufficiently to bring one of the pockets 5^a into position to discharge its contained bottle into a holder 1^a. As the pawl 7 is brought forward by this movement the coin falls from the downwardly inclined receptacle 7^d into a suitable container. Imme-

diately the weight 7^b and spring 7^c shift the pawl so that the notched portion thereof is carried radially outward beyond the path of the lugs 6^a and so that there will be no interference between said parts, as the 70 handle is returned to its normal position. As shown in Fig. 5 the notch for engaging the lugs 6^a is offset inwardly from the body of the coin receptacle 7^d.

As shown, the teeth of the gear 6 mesh 75 with the teeth on a pinion 9^a secured on the shaft of a drum 9 mounted in suitable bearings carried by the casing and adapted to turn through the lower portion of a container 10 for drinking straws 10^a. The 80 drum 9 is provided with peripheral pockets each adapted to receive a single straw and the parts are so proportioned that at each actuation of the rotary bottle delivering device a straw will be delivered by the drum 85 9 into recesses 5^b formed in the solid portions of the disk 5 intermediate the pockets 5^a. The extent of movement imparted to the bottle delivering device by the handle 4^a is sufficient to deliver a bottle on to the 90 holder 1^a and also to permit the drinking straw, supported in the recesses 5^b immediately in the rear of pocket 5^a from which said bottle is discharged, to escape from the casing and fall into said holder 1^a. The latter may be of any suitable form, but as shown, is a tubular, inclined casing through 95 which the bottle and straw will slide to the open end at the left side of the machine.

Referring particularly to Fig. 4 it will be 100 seen that the lower section of the floor or bottle support from which the delivery device successively withdraws the bottles is slightly longer than the combined lengths of the diameters of the bottles that can be supported thereon. As previously noted, the pockets 5^a are slightly less in depth than the diameter of a bottle and therefore the lowest bottle in the machine will be supported 105 partly by the delivery device and partly by said inclined floor. As the delivery device is rotated from the position shown in Fig. 4, it will be seen that a rotating and slightly rearward movement will be imparted to the bottles resting on said forward floor section and not engaged by the delivery device. This rotary movement is imparted to the bottle or bottles resting on the lower tier and such relative movement between the bottles, although slight, acts to prevent the undesirable "bridging" that has heretofore 115 been the most common cause why machines for similar purposes have proved inefficient. Further, it will be noted that the bottles resting on the rear section of the floor or bottle support are not in contact one with another. This is effected by providing said section of the bottom with a rod or bar 11^a on which are a series of projections 11^b adapted to hold the bottles in the relative 120 125 130 positions.

position shown when first placed in the machine. Said rod is mounted in a suitable groove in the floor-like support and extends through an opening in the rear wall of the 5 casing where it is provided with a handle or crank by which it may be turned so that the projections 11^a thereon will be caused to lie flush with or below the level of the floor and offer no obstruction to the forward move- 10 ment of the bottles, as the delivery device operates. It will be understood that the rod 11 is only maintained in the position shown in Fig. 4 while the machine is being filled and that after the desired number of bottles 15 has been placed therein the lower tier will be held in the relation shown by the weight of the bottles super-imposed thereon.

An inclined abutment 12 prevents the bottles in layers above the lower one from extending as far to the rear as those on the supporting floor and maintains the relation between the several layers that is illustrated in Fig. 4. Similar abutments 12^a, 12^b are shown on the front wall of the casing above 25 a supplemental floor 12^c. This arrangement prevents the bottles in different layers from becoming wedged between adjacent layers and the walls of the casing. To assist in guiding the bottles to the delivery device the 30 machine is provided with two rods 13, 13^a which are hinged at their rear ends to the auxiliary bottle support 12^c and are supported at their forward ends by flexible means 13^b, 13^c. These guide rods contact 35 with the necks of the bottles and with the bodies near the ends thereof. Occasionally there will be a slight disalignment of the bottles longitudinally and therefore these guide rods are, as stated, flexibly supported 40 at their forward ends so that either may yield slightly vertically independently of the other and offer no hindrance to the desired forward movement of the bottles.

The rotary movement imparted to the bottles adjacent the delivery device as the latter is rotated is produced not only by the action of the bottle in the pocket immediately in alignment with the lowest layer of bottles, but also by the particular shape of 50 the solid portions of the disks 5 intermediate of the pockets 5^a. These parts as they pass the opening in the front wall of the bottle compartment of the casing impinge on the forward bottle of the lowest 55 layer therein and insure that the same will be loosened from any binding action exerted by the other bottles so as to immediately roll into the following pocket 5^a as the same comes into proper position.

60 The machine is provided in its front wall with means for removing the metal caps by which bottles of the character heretofore referred to are commonly provided, such means being shown in detail in Fig. 8. As shown 65 in that figure a suitable slot in the wall of

the casing is provided with a metal face plate 14 that projects slightly beyond the upper wall of the slot and a spur 14^a is provided for engaging the flat top surface of the removable cap. By simply inserting the 70 bottle in the slot so that the cap is sufficiently engaged by the spur 14^a and moving the body of the bottle downward the metal cap is readily disengaged and will fall through a suitable chute into a receptacle 15 75 provided within the casing. This feature of the invention is of importance as it provides a ready means for collecting the removed caps which, if not thus collected, are unsightly and can only be disposed of by 80 special care and attention. Further, these caps are of considerable value as premiums and it is therefore desirable to save the same.

As heretofore indicated, the machine also includes means by which the empty bottles 85 may be saved. The cost of bottles required for use with such a machine is, of course, considerable and as said bottles may be used repeatedly it is desirable to prevent their being carried away or destroyed. Therefore 90 means are provided by which the purchaser of a bottle after emptying the same may return the empty bottle and receive a valuable 95 consideration therefor. As shown, the machine is provided below and in front of the 100 bottle delivery device with an empty bottle receiver 16. This comprises a body mounted on trunnions 16^a and adapted to receive a single bottle, the depth of said receiver being a little less than the bottle to be inserted therein so that the closed, base, end of the latter will project slightly as represented in dotted lines in the drawings. This receptacle is arranged within a suitable auxiliary casing having at its upper end an 105 opening 16^b through which the bottles may be inserted and provided in its front wall with a slot through which projects a handle 16^c by means of which said bottle holder 16 may be rocked to a position where the bottle 110 contained therein will automatically, by gravity, slip out into the interior of the casing. Means are provided by which the empty bottle in passing into the casing will coöperate with a coin delivering mechanism 115 so that a coin will be discharged through an outlet at one side of the machine. In employing a machine constructed in accordance with the present invention it is designed, for example, to require the deposit 120 of a dime in order to properly position the pawl 7 for actuating the bottle delivering device and also on the return of the empty bottle to the casing, to discharge a nickel so that the actual or net cost of the contents of 125 the bottle will be but five cents.

17 designates a receptacle, shown as having the form of a tube in which a series of five cent pieces, for example, may be super-imposed and 18 designates a slide 130

which reciprocates across the lower end of said tube and the mouth of a delivery channel or way 19, said slide being adapted when in one position, as for example that shown in dotted-lines in Fig. 3, to have a lateral projection thereon positioned in the rear of the lowest coin in the tube 17 and when moved into the position represented by full lines, to discharge said coin into the delivery passage 19. To effect these movements said slide is connected at one end with a lever 20 fulcrumed at 21 and having one arm provided with a lateral projection that extends into the path of the portion of the empty bottle that projects from the receptacle 16. Therefore, as said receptacle 16 is rocked the lever 20 will be turned by the engagement of the empty bottle with said lateral projection 22, the empty bottle sliding over such projection into the interior of the casing as it leaves the receptacle 16. This movement of the lever 20, as above explained, positions the slide so that the coin engaged thereby is brought into alignment with the chute 19 and is discharged. The slide 18 is of the same or slightly less thickness than the coins to be discharged and when the parts are positioned as indicated in full lines, the lowest coin is in front of the projection in said slide and is supported by the base or support for the tube 17. An arm 23 extends upwardly from the slide 18 into the path of the lugs or projections 6^a on the gear 6 of the bottle delivery device. Therefore, when this device is actuated by the handle 4^a the slide 18 will be moved into the position represented in dotted lines in Fig. 3 where the lowest coin in the tube 17 will be positioned in such relation to the slide as to be moved thereby over the discharge tube 19 when the lever 20 is again rocked by the return of an empty bottle to the casing. The receptacle 16 will be normally maintained in its vertical position shown by gravity, or any other suitable means, and will return to said position automatically on the empty bottle being discharged therefrom. To prevent the bottles from being broken by falling after leaving the receptacle 16 it is proposed to provide in the bottom of the casing a suitable stop 24 having a padded or cushioned top against which the bottles will strike and from which they will roll or fall into the body of the casing. To prevent improper actuation of the coin delivering means a shield 17^c is connected with the handle 16^c so that as the bottle receptacle is turned by moving said handle upward the opening 16^b will be closed.

It will be evident that instead of using coins to shift the pawl 7 and in the tube 17 suitable checks corresponding to the necessary coins may be employed. Therefore, in the following claims the term "coin" is in-

tended to include such checks as well as actual money.

Also while in the foregoing specification reference has been made to "dimes" and "nickels" it will be understood that coins of other denominations may be used if desired.

The lever 20 and coin slide 18 cannot be actuated by turning the bottle holder 16 unless a perfect bottle is positioned therein. That is, said lever is rocked by contact therewith of the portion of a bottle that projects from the holder and therefore a bottle, the neck of which has been broken, so that it would not project from holder 16, could not be used to operate the coin slide.

After the coin delivery slide has been actuated by returning a bottle to the casing it is impossible to obtain another coin from the chute 17 until the delivery device has been again actuated following the deposit of a coin that will render the pawl 7 operative.

Having thus described my invention, what I claim is:—

1. In a machine for the purpose described, the combination of a support for a series of bottles, a delivery device adapted to withdraw bottles successively from said support, coin controlled means for intermittently actuating the delivery device, a coin receptacle, and means for discharging a coin from said receptacle arranged to be controlled by the bottle delivering device.

2. In a machine for the purpose described, the combination of a support for a series of bottles, a delivery device adapted to withdraw bottles successively from said support, coin controlled means for intermittently actuating the delivery device, a coin receptacle, a reciprocating means for ejecting coins from said receptacle successively, means actuated by the bottle delivery device for moving said ejecting means in one direction, and means arranged to be actuated by returning a bottle to the machine for moving said reciprocating means in the opposite direction.

3. In a machine for the purpose described, the combination of a support for a series of bottles, a rotary delivery device adapted to withdraw bottles successively from said support, coin controlled means for intermittently actuating said delivery device, a coin receptacle, and means arranged to be actuated by the bottle delivery device and by the return of a bottle to the machine for successively discharging coins from said receptacle.

4. In a machine for the purpose described, the combination of a support for a series of bottles, a delivery device adapted to withdraw bottles successively from said support, coin controlled means for intermittently actuating said delivery device, a coin receptacle, a reciprocating slide adapted to move into

- and from position to receive a coin from the receptacle, means actuated by the bottle delivery device for moving said slide in one direction, and means actuated by returning a bottle to the machine for moving said slide in the opposite direction, whereby by returning a bottle to the machine after actuating the delivery device, a coin will be discharged from said receptacle.
- 10 5. In a machine for the purpose described, the combination of a support for a series of bottles, a delivery device adapted to withdraw bottles successively from said support, coin controlled means for intermittently actuating said delivery device, a coin receptacle, a reciprocating slide adapted to move into and from position to receive a coin from the receptacle, means actuated by the bottle delivery device for moving said slide in one direction, and a lever connected with said slide and adapted to be actuated by returning a bottle to the machine to move said slide in the opposite direction, for the purpose specified.
- 25 6. In a machine for the purpose described, the combination of a support for a series of bottles, means adapted to withdraw bottles successively from the support, coin controlled means for intermittently actuating the delivery device, a coin receptacle, and means for delivering a coin from said receptacle adapted to be actuated by said coin

controlled means and the return of a bottle to the machine.

7. In a machine for the purpose described, 35 the combination of a support for a series of bottles, means adapted to withdraw bottles successively from the support, coin controlled means for intermittently actuating the delivery device, a coin receptacle, means 40 adapted to be positioned to receive a coin from said receptacle by movement of said coin controlled means, and a pivotally mounted receiver for a bottle adapted to return a bottle to the machine and effect 45 movement of said coin receiver to discharge the coin therein.

8. In a coin controlled bottle vending machine, the combination of a casing adapted to receive and support a series of bottles, a 50 device for successively delivering bottles from the casing, a receptacle for a stack of coins of less value than the selling price of a bottle to be delivered by the machine, coin controlled means adapted to actuate the delivery device, means adjustable by the delivery device to engage the lowest coin in said stack, and means adapted to be actuated by returning a bottle to the casing for withdrawing said engaged coin from the coin 55 receptacle.

In testimony whereof I affix my signature.

HENRY JEFFERSON DAVIS.
